UNITED STATES PATENT OFFICE.

THOMAS H. SAVERY, OF WILMINGTON, DELAWARE.

PAPER-MAKING MACHINE.

SPECIFICATION forming part of Letters Patent No. 611,421, dated September 27, 1898.

Application filed November 14, 1896. Serial No. 612,099. (No model.)

To all whom it may concern:

Be it known that I, THOMAS H. SAVERY, a citizen of the United States, residing in the city of Wilmington, county of New Castle, and

5 State of Delaware, have invented certain new and useful Improvements in Paper-Making Machines, fully described and represented in the following specification and the accompanying drawings, forming a part of the same.

10 This invention relates to paper-making machines, and more particularly to an improvement upon the subject-matter of my application, Serial No. 612,098, executed and filed of even date herewith.

15 The object of the present invention is the rapid and continuous removal of the water which is expelled from the forming paper through pressure applied thereto by the moving cylindrical surfaces between which it

20 passes, and which water enters into the angular space existing between the carrying-felt and the couch-roll of a cylinder-machine, between the forming-wire and the couch-rolls in a Fourdrinier machine, and between the car-

25 rying-felt and the press-rolls in all paper-making machines and would exist between press-rolls if the carrying-felt were omitted. This angular space constitutes a recess at the front or entrance side of such rolls in which

30 a body of this expelled water ordinarily accumulates and is maintained and from which it is thus enabled to reenter the paper stock or stuff or its traveling support or carrier thereof, from either or both of which it was

35 derived, and thereafter act injuriously by staining the forming paper by rewetting the paper stock or stuff or its support or carrier, and thereby necessitating more extended operations in the forming of the paper or ren-

40 dering the devices which aid in the formation of the paper defective in their operation.

The invention consists of a pneumatic appliance for continuously removing water from said recess, whereby the water received therein instead of accumulating there is constantly discharged therefrom, and thus is prevented from returning to the paper stock or stuff or to the devices operating in connection therewith and injuring the paper or causing defective action of said devices, all of which, together with the benefits consequent upon this invention, are hereinafter fully set forth.

The specific embodiment of this invention herein embraced is a pneumatic appliance which, broadly stated, is a means for removing this objectionable body of water by the operation of air thereon, and more limitedly set forth is the provision of said recess with an air-exhaust apparatus whereby the water when received within said recess from the forming paper is rapidly removed therefrom and discharged from the machine.

Preferable embodiments of this invention are illustrated in the accompanying drawings, wherein—

Figure 1 is a diagrammatic side elevation showing the same as applied to a cylinder paper-making machine. Fig. 2 is a similar view showing the said invention as applied to the couch-rolls of a Fourdrinier machine. Fig. 3 is a similar representation of a first pair of press-rolls applicable to either a cylinder or Fourdrinier machine and provided with this invention. Fig. 4 is a similar representation of a second pair of press-rolls similarly equipped. Fig. 5 is a sectional elevation, one-half ordinary practical size, of so much of a cylinder paper-machine as will exhibit the relation of its forming-cylinder, couch-roll, web of stuff, forming-felt, and the pneumatic appliance in their correlations. Fig. 6 is a like-sized elevation of part of the pneumatic appliance, couch-rolls, endless wire apron, and stuff or stock. Fig. 7 is a like-sized elevation of part of the pneumatic appliance, first press-rolls, and endless felt. Fig. 8 is a like-sized elevation of part of the pneumatic appliance, second press-rolls, and endless felt; and Fig. 9 is a plan view of a modified form of the pneumatic appliance.

It will be observed in the case of a cylinder machine (illustrated in Fig. 1) that the forming-cylinder 4 is a reticulated cylindrical surface, which in practice turns in a vat (not shown) and for the most part is immersed in a mass of diluted pulp or stuff constantly supplied thereto, as is common. This forming-cylinder is surmounted by another cylindrical surface or couch-roll 5, and the forming-felt 6, which runs under and returns over the couch-roll, also passes in contact with the top of the forming-cylinder, and consequently since the film of fibers or web of stock or stuff 3 taken up by the forming-

cylinder upon its onwardly-moving surface is first carried against the under side of the forming-felt 6 and passes therewith to and between the cylindrical surface of the forming-cylinder 4 and that of the couch-roll 5 it results that the pressure thus exerted upon it expels from it a large portion of the water it then contains, much of which water will pass upwardly through said forming-felt 6 and be received in the recess formed at the front side of the couch-roll 5 and between it and the forming-felt 6, as is best understood from Fig. 5. While the water thus delivered into this recess and accumulated on top of the felt 6 may have its excess spread rearward upon said felt 6 and be carried off the same from the sides thereof, there will always be a portion of this accumulating body of water retained in said recess sufficient to substantially fill it, such water being maintained therein either by gravity, owing to the fact that said recess is lower than the plane in which that portion of the felt 6 rearward of it runs, or by the action upon the water of the forward travel of the felt 6 on the cylinder 4 or by the onward movement of the surface of the couch-roll 5, or both conjointly. Such a body of water maintained in this recess will either by capillary attraction, greatly aided by the damp condition of the felt 6, its onward movement, or the forward travel of the cylindrical surface of the cylinder 4 and that of the couch-roll 5, reenter the wet web of stock or stuff from which it was expressed and stain the same, whether or not it has accumulated impurities, and thus damage it, or retard the forming operation. In order to constantly remove this water from said recess and the similar ones at pairs of cylindrical surfaces, as couch-rolls 7 8 and press-rolls 11 12 or 13 14, and to keep it clear thereof, so as to avoid not only its defective action but form the paper as dry as possible at each stage of the operation thereon where water is expelled therefrom, such recess (it may be one or more in each machine) is provided with a pneumatic apparatus operating to remove the water as it is received in such recess and thus keep the same free and clear of it.

The illustrative pneumatic apparatus in the form shown consists of a hollow or box-like structure provided at its forward end with an opening or mouth extending the full length, or nearly so, of the said recess, and so reaching and tapping it that a body of air forcibly moved within said box through its mouth will operate to discharge said water rearwardly from said recess, and thereby not only cause it to be removed from this recess, where it would otherwise act injuriously, but discharge it from the machine. At some convenient point—say the rear—at one or both sides, as may be found desirable, this structure or air-controlling chamber 10 is provided with a pipe 20, by which it is connected to a suitable pump, as an air-pump, for exhausting the air

from said chamber. Of course, if found necessary, this chamber might be perforated at a suitable point or points sufficiently to admit air to aid its practical operation; but it will ordinarily be found that there will be leakage sufficient past one or the other or both of its lips 1 2 to promote a suitable draft that will effect the removal of the water entirely from the said recess and as rapidly as it accumulates therein or it is expelled from the wet stock or stuff 3 and passed into such recess, and to effect this leakage past the preferred one of these lips the other may be made of stiffer material, so as to hold its place close to or in contact with the roll and the felt or wire, as the case may be. There are many devices or apparatus by which this movement of water can be effected through the force of air either acting by suction or pressure; but as a pressure apparatus adapted for this purpose is made the subject-matter of another application it is only alluded to herein to indicate the scope of the present invention, and the suction or draft force of air and the appliance for so using it will be set out herein and specifically claimed.

Referring now to the pneumatic appliance shown in reduced scale by Fig. 1 as applied to a forming-cylinder 4 and its couch-roll 5 and illustrated in Fig. 5 at a half-normal size, it will be observed that as the movement of the water expressed from the saturated web of stock or stuff 3 is upward through the felt 6 the air appliance must be adapted to that condition of affairs. A structure suited thereto is shown as consisting of a chamber provided with a pipe 20 and closed on all sides save where its mouth or orifice embraces or taps the said recess between the forming-felt and the couch-roll, and the lips 1 2 of its mouth are preferably caused to contact, respectively, with the surface of the felt 6 at its bottom and with the surface of the couch-roll 5 at its top, a constant draft or induction through it being caused by the action of the pump or other air-current-producing apparatus that is connected with the pipe 20. It may now be understood that as this forming-cylinder 4 slowly turns in its vat in the direction of its arrow its action will be to take up upon its side, as indicated in Fig. 1, a film or strata of fibrous stuff or stock 3 that is surcharged with water and carry the same in web-like form upward and onward toward the couch-roll 5. This stock or stuff in passing between the top surface of the forming-cylinder 4 and the under surface of the forming-felt 6, which is an endless apron that travels over said couch-roll, will be simultaneously pressed between these devices and caused to adhere to the felt 6. At the same time much of the water with which it is charged will be pressed through said felt and enter into the recess between the upper side of the felt and the front side of the couch-roll and therefore enter within the sphere of action of the current of the moving air, said

water upon coming within the range of the passing current being at once carried rearward thereby through the pipe 20 and discharged with the said air-current. This air-current thus acts continuously to remove whatever water enters the said recess and comes within the range of action of the air, which in practice is found to be equal to the entire removal of this water, which fact therefore prevents its accumulation in said recess to produce any faulty action.

It is preferable to cause the induction of air in excess of that which accompanies the water or otherwise leaks into the recess to enter the air-chamber between its upper lip 2 and the couch-roll 5, for the reason that the direction or guiding of said air by the curved surface of the couch-roll will be such as to aid its entering to the extreme forward point of said recess and thus so act that it may thoroughly clean the same as it takes its outward movement for discharge. It may, however, take such air from between the lower lip 1 and the felt 6 or partially past both the upper and lower lips.

Regarding now Fig. 2 and the sectional enlargement of its parts in Fig. 6, the air-chamber will be found to be slightly modified to suit the relative disposition of the couch-rolls 7 8 and the wire apron 9, as will be apparent from an inspection thereof, and it may be remarked that here it is desirable to have the excess of working air necessary to the practical operation come from between the lower lip 2 of the mouth of the air-chamber and the lower couch-roll 8, not only so as to compel the best direction of the air, but to avoid any great current near the wire apron outside of the air-chamber; but the surplus supply of air may pass either or both of said lips, as before explained. In practice it will be found that the stretch of the wire apron 9 over a portion of the lower surface of the upper couch-roll 7 will cause some water to be given off before this pneumatic device is reached and descend into the floor-vat beneath and that the nip of the two couch-rolls 7 8 will by their pressure expel from the stock or stuff itself additional water, which will flow into the recess that exists between these couch-rolls at their front or entrance side and be removed by the air drawn through the air-chamber by the pipe 20, which will operate in manner as before explained; but in some cases, if found desirable, the mouth of this air-chamber may be enlarged in its scope, so as to remove not only the water from this recess as rapidly as it is received therein, but such water as is freed by such stretch of the apron, and discharge the same out of the machine. This air device as applied to press-rolls, as 11 12 and 13 14, is exhibited in reduced form by Figs. 3 and 4 and in one-half normal size by Figs. 7 and 8 and will, although it operates in connection with a felt, as 15 or 16, perform in the same way as has been explained with reference to the couch-rolls,

though the appliance itself in consequence of the diminished amount of water respectively expressed by these press-rolls in succession may be made relatively somewhat smaller.

As illustrated, the air-chamber 10 is shown as supplied at one end with a discharge-pipe 20, which in turn in each instance is connected with a pipe 40, leading to an air apparatus or pump, by which the exhaust of air is accomplished. These pipes are shown as provided with cocks 21, which is to indicate that any form of valve or gate that may be suitable therefor may be used to control the amount of air used or its pressure, which may thus be made to differ in force at different places, which is sometimes desirable. It is also important, especially when this air apparatus is used in connection with press-rolls and because of the freedom with which the water expressed by them may pass from between them at their ends and become absorbed by the overhanging felt, to exert a greater degree of exhaust near the ends of the rolls than is used throughout the main portion thereof, and for this reason it is desirable to divide the air-chamber into sections, so that by suitable pipes and means for controlling the passage of the air therethrough the draft of air may be made greater at some points than at others. This is shown in the structure illustrated in Fig. 9, where the air-chamber is divided by two partitions into three subchambers 25 26 27, so that the exhaustive power of the air may, through suitable pipes 20 30 50, be made to differ in each subchamber and have greater force at the ends than in the middle, if desired.

Concerning the damaging effect of water made use of in the production of paper it is to be noted that where water, even though it be pure, is allowed to soak into a paper web by moving backward into the same after it has been expelled therefrom it has the effect to impart to the web stains that present irregular bounds or form waved lines, which are the limits to which this returning water extends before it is so far absorbed as to cease its movement. These stains are readily perceived in the finished paper and cause the sections of the web containing them to be useless, which damaging action of the water, pure or impure, is prevented by this invention.

In some cases the stock or stuff undergoing formation into paper may be so far freed from water as its leaves the couch or first press rolls that it can be led to and passed through the first or second press-rolls without the aid of a carrying-felt, in the absence of which felt this invention will coat with the paper web, stock or stuff, and a press-roll and operate to almost completely remove its remaining dampness, and such arrangement is therefore comprehended by this invention. By the use of this invention the water is removed from said recess as rapidly as it is expressed from the stock or stuff by means which have a posi-

tive action thereon, and the following advantageous results are obtained: A high speed of production may be attained, for the reason that the paper becomes stronger because drier 5 at all stages of its formation. Larger couch and press rolls may be employed, the number of sets of press-rolls may be reduced, and a less extent of drying-surface be required or less heat needed for the drying operation.

- 10 Another and important beneficial effect is produced by this improvement upon the endless felts, which in order to produce the best results are made wider than the press-rolls are long, whence it results, since such projecting 15 parts are not clamped between the rolls, but, on the contrary, are free and therefore in the best condition to readily absorb water if the same is present in said recess between the press-rolls. The result is when the water is 20 present there and the edges of the felt become charged with it they not only carry the water onward and fling it over the machine, but in consequence of such wet edges being in contact with the paper web after it has passed 25 the press-rolls they give off the water they carry to the edges of the paper and thus impregnate the otherwise drier body of the web with water, so that the pressing and drying thereof must be great enough for the treatment 30 of the wet edges or, otherwise stated, in excess of what is required for the body portion.

In consequence of the fact that this improvement prevents the return of practically all water that is once removed from the stock 35 and the wire or felt carrying the same with the advantages already stated it also results in causing the forming paper to be made drier in the earlier stages of and throughout its formation, and therefore enables its course 40 of travel to be lessened and permits of a reduction of the great length in which these machines are now constructed.

The application of these improvements to a paper-machine enables stronger paper to 45 be made, because being formed drier it does not require to be heated so much and injured thereby. It enables more paper to be made in a given time, because in the web state it is drier, and hence not so liable to break and 50 make waste. It saves the felt of the driers from injury, because a lower degree of heat may be used, and the paper when led to them not being so wet as when made by a machine without this improvement there is less wetting 55 and consequent drying of said felts, which rots them. It improves the quality of the paper by running faster, because there is less water to take out of it during the greater portion of its formation, and by its action it 60 keeps impurities from entering the felts and thus soiling them, so that they require frequent washing, which is detrimental in that felts frequently washed are thereby worn out and rendered useless, and it prevents the 65 edges of the press-felts from receiving water and carrying it into the borders of the paper beyond the rolls.

It may be desirable to provide the lips 1 and 2, either or both, with a facing of leather, rubber, or similar material having the required 70 strength and pliability for contact with the parts they may bear against in order to prevent injury thereto or produce a proper joint therewith.

Although broadly embraced herein, the 75 pneumatic appliance employing a blast of air for carrying out this invention is reserved as the subject-matter of another application, Serial No. 612,100, filed by me of even date herewith. 80

What is claimed is—

1. The combination with cylindrical surfaces between which wet stock is fed and by the action of which the liquid is expressed from the stock into the recess between the 85 surfaces, of a pneumatic appliance exterior to said surfaces and operating to remove the liquid directly from the said recess, substantially as described.

2. The combination with a traveling support, of cylindrical surfaces between which wet stock is fed by the traveling support whereby the liquid is expressed from the stock into the recess between the surfaces, and a pneumatic appliance exterior to said 95 surfaces and operating to remove the liquid directly from the said recess, substantially as described.

3. The combination with cylindrical surfaces between which wet stock is fed whereby 100 the liquid is expressed from the stock into the recess between the surfaces at the entrance side thereof, of a pneumatic suction appliance exterior to said surfaces and acting to remove the liquid directly from the 105 said recess, substantially as described.

4. In a paper-making machine, the combination with a traveling support, of cylindrical surfaces between which wet stock is fed by the support whereby the liquid is expressed 110 from the stock into the recess between the surfaces at the entrance side thereof, and a pneumatic suction appliance exterior to said surfaces and operating to remove the liquid directly from the said recess, substantially 115 as described.

5. In a paper-making machine, the combination with cylindrical surfaces between which wet stock is fed and by the action of which the liquid is expressed from the stock 120 into the recess between the surfaces at the entrance side thereof, of a pneumatic appliance consisting of a chamber provided with a mouth or orifice, the said mouth or orifice being located exterior to said surfaces and 125 acting to remove the liquid directly from said recess, substantially as described.

6. In a paper-making machine, the combination with a traveling support, of unbroken cylindrical surfaces between which wet stock 130 is fed by the support whereby the liquid is expressed from said stock into the recess between the surfaces at the entrance side thereof, and a pneumatic appliance consist-

ing of a chamber provided with a mouth or orifice, said mouth or orifice being located exterior to the surfaces and operating to remove the liquid directly from said recess, substantially as described.

7. In a paper-making machine the combination with a traveling support, of cylindrical surfaces between which wet stock is fed by the support whereby the liquid is expressed from the stock into the recess between the surfaces at the entrance side thereof, and a pneumatic appliance consisting of a chamber divided by partitions into subchambers each subchamber being provided with a mouth or

orifice which is exterior to said surfaces and which operates to remove the liquid directly from said recess, and connections whereby a different degree of air force is exerted in some chambers to that which is exerted in other chambers, substantially as described. 15 20

In testimony whereof I have hereunto set my hand in the presence of two subscribing witnesses.
